UNITED STATES PATENT (

JOHN H. SAYRES, OF BROOKLYN, NEW YORK.

SASH-BALANCE CONNECTION.

1,171,257.

Specification of Letters Patent.

Pate

Application filed September 27, 1912. Serial No. 722,671.

To all whom it may concern:

Be it known that I, JOHN H. SAYRES, a citizen of the United States of America, and residing in the borough of Brooklyn, in the county of Kings and State of New York, have invented a certain new and Improved Sash-Balance Connection, of which the following is a specification.

My invention relates to sash balance connections, particularly for use with sash supporting chains, and the object of my invention is to provide a simple and quickly adjusted connection, economical to manufacture and efficient in operation.

15. In the accompanying drawing, Figure 1 is a broken section showing an installation in which a sash balance connection embodying my invention in one form, is used; Fig. 2 is a perspective of the connection alone.

2 is a perspective of the connection above,
20 Figs. 3 and 4 are side elevations showing
one manner of application of the chain
thereto; Fig. 5 is a similar view showing
another manner of attaching the chain;
Fig. 6 is an end elevation of the connec-
25 tion; Fig. 7 is a side elevation showing a
third manner of applying the chain; Figs.
8 and 9 are respectively side elevation and
plan of a modification of the connection;
and Fig. 10 is a perspective of another
30 modification.

The present connection is designed primarily for use with chain supports. Thus the installation illustrated in Fig. 1 shows an open-link chain 10 of common type, one end of which is held in a pocket 11 in the side of the sash 12 by a fastener 13 of the type shown in my prior Patent 884,344. It is to be understood however, that my present invention is not limited either to the particular style of chain illustrated or to use in combination with this particular style of sash chain fastener.

Passing over the pulley 14, the other end of the chain is secured by my improved connection 15 to the eye 16 of any suitable weight 17, here shown of the sectional type. In the form illustrated, my improved connection comprises a length of wire bent back upon itself at 18 and curved to form an open loop, the ends 19 and 20 of the wire

being angled toward each other, and preferably bent into hook and loop, while substantially spaced apart to form an open loop, in order to prevent entanglement of the chain.

site sides of the wire is narrow enough to prevent the chain from twisting into flat position beneath the bend. Where this arrangement would result in the passage of 5 the chain edgewise over the pulley, this may be avoided by so forming the connection so that the mid-bend 18 lies at right angles to the end bends 19 and 20 as shown at 22 in Figs. 8 and 9. This brings the chain 10 flat beneath the end bends, just as in the assembly shown in Figs. 3 and 4 where the neck end of the link is threaded on the loop.

A possible, but less desirable installation is 15 shown in Fig. 7 in which case the chain is passed beneath the mid-bend 18 and the open end of the terminal link threaded over the end bends 19 and 20, so that both of the latter are embraced by the link.

20 Another modification is shown in Fig. 10 where only one end 23 of the wire is angled, the other end 24 being left straight. Except that it is slightly less easy to pass the body of the chain between the ends, this construction 25 is perfectly efficient so long as the terminus of the end 23 is brought down far enough to meet or slightly overlap the end 24.

The present connection may be used with 30 any open-link chain whether large or small, and as illustrated, may be attached to either end of the chain without the use of pincers or other appliances. The broad supporting surface afforded by the opposite sides of the 35 loop, prevents the swiveling of the weight on the connection and consequently the weight is held square in its well. The chain is not weakened in any way, and the strain upon the terminal link is imparted in normal 40 manner so as to secure the full strength of the chain construction. Being made of a single piece of wire, the connection is of a uniform strength throughout its length and is readily and cheaply made.

45 Obviously the particular forms shown are merely illustrative examples of my invention and may be modified in various ways. While the wire employed for the connection may be of spring steel this is not essential 50 inasmuch as there is no possibility of the end bends 19 and 20 straightening out under the relatively light strain to which they are subjected, while any chain which could be used with this connection would break before 55 the end link could break the wire at its mid-bend 18, where these are both of usual weight. Again my connection may readily be formed by an expanded metal process instead of by wire bending.

60 I claim as my invention:—

1. A suspension hook for a sash weight comprising a single wire doubled back upon itself to afford a double strand curved in the direction of its length to form an open

loop having two strands to pass through the 65 weight eye, and means at the opposite ends of the hook to engage a sash chain, said means at one end of the loop comprising the oppositely bent ends of the wire lying substantially in register and normally spaced 70 apart in the plane of the loop to facilitate the adjustment of the chain, substantially as described.

2. A sash weight connection comprising an open metallic loop, the sides of which are 75 spaced apart transversely to the plane of the loop to accommodate a suspension chain between the same, and the ends of which are provided with cross members on one of which may be threaded a link of a suspension 80 chain engaged beneath the cross member at the opposite end of the loop, substantially as described.

3. A sash weight connection of the type 85 described, comprising a wire bent to form an open loop one leg of which is longer than the other and having chain-engaging bights at the opposite ends of the loop, said loop in operating position having its shorter leg passed through the eye of a sash weight 90 while the longer leg overlies said eye with its bight to one side thereof and substantially vertically above the bight of the shorter leg, in combination with a sash chain passing freely through the bight of the 95 longer upper leg of the loop and having its terminal link threaded into engagement with the bight of the shorter leg of the loop, whereby under operating conditions the chain extends substantially vertically to the 100 bight of the shorter leg of the loop with the result that practically the entire strain of the connection is taken by the bight of the shorter leg of the loop and by the terminal link of the chain lying vertically in normal 105 position of greatest strength and at a point of attachment substantially level with the top of the weight.

4. A sash weight connection of the type 110 described, comprising a wire bent back upon itself to form a double strand and curved in the direction of its length to afford an open loop one leg of which is longer than the other and having chain-engaging bights at 115 the opposite ends of the loop, said loop in operating position having its shorter leg passed through the eye of a sash weight while the longer leg overlies said eye with its bight to one side thereof and substantially vertically above the bight of the shorter 120 leg, in combination with a sash chain passing freely through the bight of the longer upper leg and having its terminal link threaded into engagement with the bight of the shorter leg of the loop, whereby under 125 operating conditions the chain extends substantially vertically to the bight of the shorter leg of the loop with the result that

practically all the strain of the connection is taken by the bight of the shorter leg of the loop and by the terminal link of the chain lying vertically in normal position of 5 greatest strength and at a point of attachment substantially level with the top of the weight.

In testimony whereof I have signed my name to this specification, in the presence of two subscribing witnesses.

JOHN H. SAYRES.
